UNITED STATES PATENT OFFICE.

STEPHEN P. TRAFTON, OF BOSTON, MASSACHUSETTS.

RAILWAY BUFFER-POST.

SPECIFICATION forming part of Letters Patent No. 363,438, dated May 24, 1887..

Application filed March 10, 1887. Serial No. 230,567. (No model.)

To all whom it may concern:

Be it known that I, STEPHEN P. TRAFTON, a citizen of the United States, residing at Boston, in the county of Suffolk and State of Massachusetts, have invented a new and useful Improvement in Railway Buffer-Posts, of which the following, taken in connection with the accompanying drawings, is a specification.

My invention relates to a new and useful improvement in railway-buffer-posts; and it consists in providing the same with separable buffer-blocks so arranged that they may be adjusted to suit railway-cars which have their buffers above and separate from the draw-bar, as is usually the case with passenger-cars, and those which have the draw-bar act also as a buffer, as is usual with freight-cars. I attain this object by the mechanism illustrated in the accompanying drawings, in which—

Figure 1 is a side view of my invention, and Fig. 2 an end view of the same.

Similar letters refer to similar parts throughout.

A, B, and C are timbers framed and bolted together, as shown, the timber B and the lower ends of timbers A and C being in the earth.

D is a buffer-block having a plate of iron on its outer face and bolted securely to the post A.

E is a buffer-block having a plate of iron on its outer face, but detached from the post A, being held in position by the rods *i* and *k*, which, passing freely through the block D, are, by means of the cross-bar *h* and link *g*, attached to the lever or handle F. The handle F is pivoted at *p*, and has a slot at *s*.

L is a bolt having a head suited to pass through the slot *s* on the handle F, when the same is drawn down, and by passing a pin through the hole provided in the upper end 40 secure the handle in that position.

R R represent rails, and G G sleepers.

When the buffer-blocks D E are in the position shown in Figs. 1 and 2 they may be used for cars on which the buffer is situated above and separate from the draw-bar, the space below the block D being sufficient to allow the draw-bar to pass freely, while the car-buffer will come in contact with the buffer-block D. By drawing the handle F down and securing it to the bolt L the block E is drawn upward 45 until it touches, or nearly so, the block D, forming one broad buffer-block adapted for all cars on which the draw-bar acts as the car-buffer.

I am aware that previous to my invention 55 railway buffer-posts have been made with timbers A, B, and C arranged as described. These I do not claim.

What I do claim as my invention, and desire to secure by Letters Patent, is— 60

1. The combination, in a railway buffer-post, of the movable block E, the stationary block D, the rods *i k*, cross-bar *h*, link *g*, and lever F, substantially as and for the purpose described.

2. The combination, in a railway buffer-post, 65 of the movable block E, the stationary block D, the rods *i k*, cross-bar *h*, link *g*, lever F, and post A, substantially as and for the purpose described.

In testimony whereof I have signed my name 70 to this specification, in the presence of two subscribing witnesses, on this 7th day of March, A. D. 1887.

STEPHEN P. TRAFTON.
